UNITED STATES PATENT OFFICE.

CHAFFIN C. MOORE, OF WINSTON-SALEM, NORTH CAROLINA.

DRYING CABINET.

Application filed May 31, 1927. Serial No. 195,429.

This invention relates to an improved drying cabinet made of fireproof material, and more especially to a drying cabinet in which the air is circulated properly in the cabinet 5 without the necessity of forcing the air by a fan or other means.

An object of my invention is to provide a drying cabinet for clothing and the like in which the air is so circulated as to dry the 10 clothing uniformly, and with the parts so positioned as to dry the upper portions of the garments within the same length of time required for drying the lower parts of the garments.

Another object of my invention is to provide a clothes drying cabinet with the parts so positioned as to automatically circulate the air within the cabinet as to dry 15 the clothes uniformly, and in which there are arranged a series of baffle plates and partitions to cause the air to be forced automatically to the desired portions of the garments in the desired heated state to dry all portions of the garments evenly and uniformly.

Some of the objects of my invention having been stated, other objects will appear when taken in connection with the accompanying drawings, in which—

Figure 1 is a perspective view of my drying cabinet;

Figure 2 is a perspective view of my drying cabinet with the side removed for a better showing of the interior thereof.

Referring more specifically to the drawings, the numeral 10 indicates the bottom of my cabinet while the end portions are designated by the numerals 11 and 12. The numerals 13 and 14 indicate the side wall portions of my cabinet. The baffle plates 15 and 16 are secured to the end portions by means 30 of the brackets 17, and are spaced some distance from the end portions, but are positioned vertically and parallel to the end wall portions, leaving a space therebetween.

These baffle plates have the horizontally disposed portions 18 and 19, which portions are spaced from the bottom 10, and are held in place by the brackets 20. Parallel with 40 the end wall portions and secured to the bottom member 10, is the member 21, which extends all the way across the bottom of the cabinet, and has its top portion extending some distance above the plane of the horizontal portions 18 and 19 of the baffle plates.

Resting on this member 21, and extending

from one baffle plate 15 to the other baffle plate 16 is the plate member 22, said plate member abutting against the baffle plates and the side wall portions of the cabinet. 60 A plurality of square holes therein thru which sections 23 of the system of pipes 24 project, occur in the plate 22, and these holes also serve to regulate the flow of the currents of air in the drying cabinet. Brackets 25 are secured to the bottom member 10 and project upwardly for the support of the pipes. Portions of the pipes are below the plate 22, and portions thereof are located above the plate 22, as shown in the drawings. Shutters 26 are located in the end portions 11 and 12 by means of which the amount of fresh air which is taken into the cabinet is regulated. The baffle plates extend upwardly, parallel to the end portions, and stop short of the upper ends of the end wall portions. The top portion 27 is secured to the side and end portions, and a plate member 28, of the same size as the interior of the cabinet is secured to the end and side 70 wall portions, and this plate 28 has its middle portion lowered, so as to have a trough like appearance when looked on from above. A vent or pipe member 29 penetrates the top 27 and the plate 28 and extends downwardly some distance into the interior of the cabinet to prevent the hot air from escaping from the upper portion of the cabinet, the reason being that many garments have their upper portions of double thickness, and this causes the upper portion of 80 the cabinet to be warmer than the lower portion, and thus the tops of the garments are subjected to more heat, so that the tops of the garments will be dried by the time 90 the lower portions of the garments are dried.

Rod members 30 and 31 are secured to the ends of the cabinet or to the baffle plates on which suitable clothing holders, such as coat hangers, may be placed.

One of the sides of the cabinet has a suitable door 32, to permit access to the interior of the cabinet.

The pipes are adapted to hold steam or hot water for heating the interior of the cabinet, and when heat is generated, air currents are set up which flow upward in the center of the cabinet where they strike the depressed false top, where the air currents are divided, and one half of them flow upward 105 and outward towards the end walls, thence downward between the end walls and the

baffle plates, thence between the bottom and the horizontal portion of the baffle plates, and thence upward thru the holes in the member 22, and in this way the air is circulated.

If desired the sides of the baffle plates next to the center of the cabinet may be covered with asbestos to better insulate the passages for the air currents.

10 In the drawings and specification I have set forth a preferred embodiment of my invention, and although specific terms are employed, they are used in a generic and descriptive sense only, and not for purposes of limitation, the scope of the invention being set forth in the appended claims.

I claim:

1. A clothes drying cabinet having four walls, a bottom and top, baffle plates secured 20 to the end wall portions, and having a portion thereof extending parallel to the bottom, a false bottom member secured above the horizontal portion of the baffle plates, a plurality of holes in the false bottom, a system 25 of pipes in the cabinet with a portion of the said system being above the holes, and a portion of the said system of pipes being disposed below the false bottom, and supporting means for the system of pipes, the baffle 30 plates, and the false bottom.

2. In a drying cabinet, a system of steam pipes in the lower portion of the cabinet, a false bottom in the drying cabinet, a portion 35 of the steam pipes being above the false bottom, vertically disposed members secured to the end wall portions and being spaced from the end wall portions, a false top member in the drying cabinet, the central portion of the false top member being disposed in a lower 40 plane than the end portions of the false top member, the false top member sloping gradually upward from the central portion to the end portions thereof.

3. In a clothes drying cabinet, baffle plates

secured in spaced relation from the end wall 45 portions of the cabinet, a sheet member horizontally disposed in spaced relation from the bottom member, holes in the sheet member, a system of heat conveying pipes positioned below the sheet member and having portions 50 thereof extending upwardly thru the holes and returning to a point below the sheet member, a second sheet member secured in the upper portion of the cabinet, said second sheet member having its central portion disposed in a lower plane than the end members thereof, a vent extending downwardly thru the top of the cabinet and thru the second sheet member to a point below the second sheet member, and means in the 55 upper portion of the cabinet for supporting garments during the drying operation.

4. In a drying cabinet, having top, bottom and wall portions, a flattened V-shaped, false top member secured in the top of the 65 cabinet, a partition extending across the bottom of the cabinet at a point corresponding to the lowest portion of the top false member, baffle plates secured to the end wall portions so as to leave a space between the baffle 70 plates and the end wall portion, said baffle plates extending inwardly towards each other in the same horizontal plane as the bottom member so as to leave a space between the extensions and the bottom member, a 75 false bottom member secured about the baffle plate extensions and resting on the partition, a plurality of holes in the bottom member and a steam pipe line having portions thereof extending up through the holes of the bottom members, with other portions thereof 80 extending below the bottom members, and means in the top of the cabinet for supporting garments during the drying operation.

In testimony whereof I affix my signature.

CHAFFIN C. MOORE
